UNITED STATES PATENT OFFICE.

JABEA F. SHAWHAN, OF DAYTON, OHIO, ASSIGNOR, BY MESNE ASSIGNMENTS,
TO FREEMAN B. DICKERSON, OF DETROIT, MICHIGAN.

ELECTRIC STREET-CAR MOTOR.

SPECIFICATION forming part of Letters Patent No. 453,216, dated June 2, 1891.

Application filed September 9, 1889. Serial No. 323,371. (No model.)

To all whom it may concern:

Be it known that I, JABEA F. SHAWHAN, a citizen of the United States, residing at Dayton, in the county of Montgomery and State 5 of Ohio, have invented certain new and useful Improvements in Electric Street-Car Motors, of which the following is a specification.

My invention relates to driving street-railway or tram cars by electricity, and has for 10 its object to drive two independently-revolving car-wheels or sets of wheels by independently-operating electric devices, and to adapt a constantly-operating automatic electric motor to street-car-driving purposes; and to 15 these ends it consists of an electric motor having two independent revolving armatures connected, preferably, by certain novel gearing described with the independently-revolving wheels of the car, and in certain details 20 of arrangement and combinations of parts to be hereinafter pointed out.

In the drawings, Figure 1 is a side view of a tram-car having my invention applied thereto. Fig. 2 is a plan view of the truck and the 25 motor carried thereby. Fig. 3 is a longitudinal sectional view through the variable reducing-gear device. Fig. 4 is a section on the line 4 4, Fig. 3, looking in the direction of the arrow. Fig. 5 is a plan view of a motor 30 connected to drive two independently-revolving wheels mounted upon the same axle.

The motor A and the storage-batteries B are supported upon a small car specially constructed and adapted therefor, the truck- 35 wheels being arranged close together with the motor between them supported upon the truck-frame, while the batteries are upon a spring-supported frame, preferably the frame of the car.

40 In the drawings, 1 1 represent the carrying and driving wheels of this car or truck mounted upon the axles 2, which run in the boxes 3, all of which parts may be of any usual or preferred construction. The longitudinal 45 sills or bars 5 of the truck are connected by the end and intermediate cross-bars 6. Above the truck-frame thus formed is another rectangular frame 7, supported upon the springs 8 and generally constituting the platform of 50 the car. The motor A is securely supported

upon the truck-frame and thus has a rigid or fixed relation to the wheels, so that a constant relation between the driving shaft or shafts of the motor and the wheels is maintained. The batteries, on the other hand, as 55 well as the platform and the top of the car, are mounted upon the spring-supported frame, which avoids jarring the batteries.

The motor consists of the field-magnets 9, between the poles of which are arranged the 60 two revolving armatures 10, with commutators and brushes in such relation to each other that the armatures are driven in unison. The shaft 11 of each armature 10 is independently connected to drive one of the pairs of 65 truck-wheels 1.

It frequently occurs that the sizes of the wheels on the different axles of a car vary from different causes, such as unequal shrinkage in casting, unequal wear or travel, &c., 70 and much difficulty has heretofore been experienced in driving such wheels from a single motor by reason of this fact, because one set of wheels with its axle tends to make more revolutions in traveling a given distance than does the other set. This is extremely destructive upon machinery where the two sets of wheels are connected with a single motor by rigid gearing. This objection has been sought to be overcome by the 75 use of two electric motors, each connected with one of the sets of wheels to be driven; but the use of two motors adds considerable more weight to be carried, and more energy is required to charge the field-magnets than 80 in one motor, which objections are overcome without any attending disadvantages or loss by the use of a single pair of field-magnets having two independent armatures connected respectively with the sets of wheels, which 85 armatures independently accommodate themselves to the different speeds of revolution of the wheels which they drive, so that there is no strain upon the motor from any variation in the revolution in the truck-wheels. 90

It is well known that it is essential in order 95 to secure the greatest efficiency of an electric motor that it should run continuously and at a high rate of speed, and this renders such motors of difficult application to street-cars, 100

which have to stop and start at short intervals and where the car-wheels travel at a lower speed than the armature-shaft.

In order to secure the advantages of the use of a continuously-moving motor and to operate the wheels from armatures revolving at high speeds, I employ the variable speed-gear device, which I will now describe. Each armature-shaft 11, Figs. 3 and 4, is provided with an eccentric 17, keyed to the armature-shaft, upon which eccentric is loosely mounted a pinion 18, which meshes with the internal teeth *a* of an annular gear-wheel 16, supported concentrically to the shaft 11. This annular wheel 16 is by preference supported by a flange 15 of a sleeve 14, which is loosely supported upon the armature-shaft, the flange tightly closing the internal opening therein of the wheel 16 on the inner side. The external teeth *b*, Figs. 1 and 3, of the annular wheel 16 mesh with a gear-wheel 19, secured either to the axle 2 of the truck or to one of the wheels thereon, the wheel 16, when in operation, serving as an idler to transmit motion from the pinion 18 to the gear-wheel 19. If the pinion 18 be perfectly free to turn upon the supporting eccentric around its own center and motion be imparted to the shaft 11, the pinion is carried around the internal gear *a* of the annular wheel and in mesh therewith, the pinion having thus imparted to it a planetary-like movement, the direction of revolution of the pinion being the reverse of that of the shaft. Under these circumstances no motion is imparted to the annular wheel 16. Should, however, the revolution of the pinion upon its own center be arrested by any means, the eccentric being loose within the pinion and carrying the latter with it around the axis of the shaft 11, still causes the pinion to travel upon the internal gear *a* of the annular wheel; but, being prevented from turning on its own center, the pinion causes the annular wheel 16 to revolve in a direction the same as that of the shaft 11, but at a much less speed.

The revolution of the pinion around its own center may be arrested in numerous ways, that which I have shown consisting of a friction device of such nature that the arresting of the revolution around its own center of the pinion and the corresponding starting of the annular wheel and the parts which it drives—from the shaft 11, which is rapidly revolving—is gradual and easy, so that shocks and strains are not experienced. The mechanism for thus gradually starting the annular wheel 16, and through it the car, consists of a grip or friction wheel and band and a loose connection between such wheel and the pinion, the parts being so arranged that when the grip or friction wheel is free to turn it is caused to rotate by the pinion as it is carried around the axis of the shaft 11 by the eccentric; but as soon as the wheel is held stationary by the grip-band the pinion, by reason of the universal movement 24, is held from

turning on its own center, while it is free to accompany the eccentric. One arrangement of grip-wheel 20 is shown in Figs. 2, 3, and 4, in which the grip-wheel is supported to turn freely upon the reduced portion 22 of the armature-shaft 11.

The grip-bands 26 are each supported at one end upon a bolt or pin 27, mounted in a bar 28, extending from some stationary part of the frame-work. The two bolts 27 are preferably connected by a cross-bar 29, which braces them apart, and, together with the bars 28, holds them in proper relation to each other and to their wheels. I prefer to operate the two bands 26 by means of a single hand-lever 30, which is connected by a link 31 with a cross-bar 32, which in turn is connected by the links 33, respectively, with the levers 34. The levers are fulcrumed in adjustable supports consisting of the screw-rods 35, mounted in the sockets 36, and are connected with the ends of the bands 26, opposite to those which are supported by the bolts 27. By moving the hand-lever in the direction of the arrow, Fig. 1, the bands and shoes will be made to grip the wheels 20, and thus stop the rotation of the pinions 18 and cause power to be transmitted to the driving-wheels 1 of the truck.

23 is an arm carried by the pinion 18 and pivotally connected at its outer end to a block 24, sliding between ways 25, formed on the grip-wheel. When the grip-wheel is held stationary the block 24 and pinion are prevented from turning; but the block is permitted to slide in and out in the ways 25 as the pinion is carried with the eccentric.

The motor which I employ is an automatic or shunt-wound electric motor and regulates the amount of current taken according to the amount of work being performed, and therefore so long as the grip-bands 26 are loose the only energy expended will be that required to overcome the friction of the bearings and to cause the pinion to revolve around the internal gear of the annular wheel. While the speed of the armature-shaft of the motors is practically uniform, whether it be running free or driving the car, I am enabled to connect the motor with the driving-wheels without any shock to the machinery, since by slowly moving the hand-lever 30 to gradually bring the grip-band 26 to bear its wheel a certain amount of slip is allowed between the band and wheel and the turning of the pinion 18 upon its center is gradually arrested and the car-wheels are started up correspondingly.

By means of the single train of gearing of the proportion shown, consisting of the pinion 18, the annular internally and externally toothed wheel 16, and the gear-wheel 19, I reduce the speed from the armature-shaft to the car-axle from 15 to 1, thus greatly reducing the amount of gearing. In order to further reduce friction and prevent noise to as great an extent as possible, I cause the pinion 18 and the sliding connection between the pinion and the grip or friction wheel to move

in oil, the internal opening of the wheel 16 constituting an oil-reservoir, the inner end of which is tightly closed by the plate 15, as before described. The outer face of the annular wheel 16 is covered and closed by the grip-wheel 20, between which and the face of the pinion is arranged a packing-ring 38, held outward by the springs 39, which ring forms an oil-tight joint, closing the oil-reservoir.

10 In Fig. 5 I have shown a motor and connections wherein the two separate armature-shafts are connected respectively with the two wheels mounted loosely upon the same axle. Such motor is intended to be applied 15 directly to the car intended for the carrying of passengers, and as I have made it the subject-matter of a subsequent application for patent, filed May 10, 1890, Serial No. 351,338, I have merely shown in a general way the 20 connections between the motor and the car-wheels, many of the details of arrangement being omitted. Similar reference-letters for like parts are used in these figures. The 25 wheels 1 are shown as carried by sleeves 45, which run loosely and independently of each other upon the axle 2. The sleeves 45 carry the gear-wheels 19, which are driven, as in the apparatus hereinbefore described, from the armature-shafts. By employing a single 30 field-magnet with two armatures not only are the objections incident to the variation in the size of the car-wheels overcome, as before described, but at the same time the advantages incident to the use of a single motor in 35 the less electric energy expended in charging the field-magnets, and the great reduction in weight, are secured.

The advantages incident to employing a 40 constantly-operating automatic motor have been set forth, as well as those incident to the variable reducing-gear connections which I have described and shown.

It will be understood that this gear connection is equally adapted for use in connection with a motor, whether electric or not, 45 having a single driving-shaft. By arranging the motor and batteries upon a separate car constructed therefor the noise of the motor and the smell of the batteries is removed 50 from the passengers, and, by reason of its being of small size, it is more readily shifted than can be a car of larger size, and turns short curves more easily. Besides, the wheels can be mounted so close together as to permit the 55 motor to be geared directly to both sets of wheels and the motor set so high as to be largely free from dust and easy of access for repairs, &c. The arrangement of the reducing-gear device (shown in Figs. 3 and 4) 60 brings the grip-wheel and the annular wheel 16 into concentric relations with each other, so that besides being able to support them

upon a common support the grip-wheel serves as a dust-guard for the internal opening into the wheel 16, in which the eccentric and pin- 65 ion operate.

Without limiting myself to the precise construction and arrangement of parts shown, I claim—

1. A motor-car having a rigid truck-frame 70 connecting rigidly the two axles, and a second frame supported by spring-bearings upon the truck-frame and connected with the body, in combination with an electromotor arranged upon the truck-frame with independent con- 75 nections between the motor and the different wheels, and batteries mounted upon the spring-supported frame, substantially as set forth.

2. The combination, with the independently- 80 revolving car-wheels on a single axle, of an electric motor having two armature-shafts independently connected to drive the said car-wheels, substantially as set forth.

3. The combination, with one or more axles, 85 of a motor consisting of two electro-magnets and two armatures and having a single magnetic circuit, the armatures being connected to propel the car, substantially as set forth.

4. The combination, with one or more axles 90 of a car, of a pair of electro-magnets and two armatures constituting a single motor having a single magnetic circuit, the motor being suspended from the axle or axles and the armatures being geared to propel the car, 95 substantially as set forth.

5. The combination, with a single axle of a car, of a motor consisting of a pair of electro-magnets and two armatures and having a single magnetic circuit, the motor being sup- 100 ported by the axle and the armatures being geared to propel the car, substantially as de- scribed.

6. The combination, with the independently- 105 revolving car-wheels, of an electric motor hav- ing a single field-magnet and two armatures operating between the poles of the magnet in a single magnetic circuit, and independent gear connections between each armature-shaft and one of the gear-axles, substantially 110 as described.

7. The combination, with a tram-car and a 115 constantly-revolving electric motor thereon, of independent car-wheels and a speed-reducing device between each car-wheel and the motor, substantially as set forth.

In testimony whereof I have signed my name to this specification in the presence of two subscribing witnesses.

JABEA F. SHAWHAN.
